[54] SNAKE HEAD SLIP SINKER[76] Inventor: Richard D. Woodard, 224 S. 16th,
Guthrie, Okla. 73044[] Term: 14 Years[21] Appl. No.: 598,174[22] Filed: July 23, 1975[51] Int. Cl. .... D22—05[52] U.S. Cl. .... D22/30[58] Field of Search 43/44.9; D22/27-29,
D22/37[56] References Cited*U.S. PATENT DOCUMENTS

3,273,278	9/1966	Lynch	..... 43/44.87
3,545,120	12/1970	Takaoka	..... 43/44.9
3,834,061	9/1974	Klein	..... 43/44.9

Primary Examiner—William N. Wertman
Attorney, Agent, or Firm—Jerry J. Dunlap[57] CLAIM

The ornamental design for a snake head slip sinker, substantially as shown.

DESCRIPTION

FIG. 1 is a side elevational view of the snake head slip sinker of the present invention.

FIG. 2 is a top plan view of the snake head slip sinker of FIG. 1.

FIG. 3 is a bottom plan view of the snake head slip sinker of FIG. 1.

FIG. 4 is a view of one end of the snake head slip sinker of FIG. 1.

FIG. 5 is a view of the other end of the snake head slip sinker of FIG. 1.

FIG. 1

FIG. 2

FIG. 3

FIG. 4

FIG. 5